CLAIM

The ornamental design for an outer cover for one-time-use camera, as shown and described.

DESCRIPTION

Reference is made commonly assigned copending applications Ser. No. 29/092,499, filed on Aug. 11, 1998, entitled Outer Cover for One-Time-Use Camera and filed in the name of James L. Shapiro, Ser. No. 29/092,059 filed on Aug. 11, 1998, entitled Outer Cover for One-Time-Use Camera and filed in the name of James L. Shapiro, Ser. No. 29/092, 058, filed on Aug. 11, 1998, entitled Outer Cover for One-Time-Use Camera and filed in the name of James L. Shapiro.

FIG. 1 is a front elevation view of an outer cover for a one-time-use camera, showing my new design;

FIG. 2 is a top plan view thereof;

FIG. 3 is a bottom plan view thereof;

FIG. 4 is a right-side elevation view thereof;

FIG. 5 is a left-side elevation view thereof;

FIG. 6 is a perspective view of the outer cover of FIGS. 1-5 placed on the one-time-use camera (shown in broken lines), as seen from the front, top and right-side of the one-time-use camera; and,

FIG. 7 is a perspective view of the outer cover of FIGS. 1-5 placed on the one-time-use camera (shown in broken lines), as seen from the rear, bottom, and left-side of the one-time-use camera.

The broken line showing of the one-time-use camera in FIGS. 6 and 7 is for illustrative purposes only and forms no part of the claimed design.

FIGS. 6 and 7 are on an enlarged scale.
